UNITED STATES PATENT OFFICE

WALTER EDWIN TRENT, OF NEW YORK, N. Y., ASSIGNOR TO TRENT PROCESS CORPORATION, OF NEW YORK, N. Y., A CORPORATION OF DELAWARE

PROCESS OF DISTILLING CARBONACEOUS MATERIALS

Application filed January 20, 1928. Serial No. 82,561.

The invention relates to a process primarily adapted for carbonizing coals and the like, although applicable for the cracking of hydrocarbon oils.

5 It is an object of the invention to provide a process in which the heat used for carrying out either the carbonizing or the cracking operation is stored within a container into which the materials to be treated are 10 deposited.

The invention more specifically relates to a process of the batch type in which the treating chamber is so constructed that it may be heated to a high temperature and 15 will absorb sufficient heat to cause a carbonization, heating, or cracking of various materials such as coals, hydrocarbon oils, etc. The process is also applicable for the heat treatment of other materials such as 20 lime and limestone.

In carrying out the process the treating vessel is preferably highly heated whereupon the material to be treated is introduced therein and the absorbed or stored heat contained in the walls of the receptacle is sufficient to cause the introduced material to undergo the desired treatment.

In carrying out my process I preferably heat a rotating chamber having walls of a 30 substantial diameter to a temperature of say 700° C. or higher, whereupon I introduce to the heated chamber coal or the like to undergo carbonization therein. The contained heat of the chamber therefore carbonizes the coal within fixed limits of temperature, giving the carbonized product a uniform texture and extracting from the succeeding batches of material undergoing treatment a more or less uniform product of 40 distillation.

The invention is capable of being carried out in various types of apparatus, but in the figure of the drawings I have illustrated a preferred form of apparatus.

45 Fig. 1 is an end view of my apparatus, showing the drum and its mounting.

Fig. 2 is a sectional view, taken along the line 2—2 of Fig. 1, looking in the direction 50 of the arrow.

Fig. 3 is cross sectional view, as seen from the end, as in Fig. 1.

Fig. 4 is a detail, partly in section, of the end closure of the drum.

Referring now more particularly to the drawings wherein like reference characters indicate corresponding parts, the numerals 1 designate supporting rollers which are mounted upon suitable shafts, two or more spaced pairs of these rollers being employed. 55 The treating or carbonization chamber comprises a metallic cylinder 2 which is of a very substantial thickness. The thickness of the cylinder, of course, depends upon the quantity of material that is to be treated 60 and the temperatures to which this material should be heated. The walls of the cylinder should range in thickness from 12 to 18 inches. The cylinder is constructed of cast iron or other metal or materials capable of 65 absorbing and storing heat. Surrounding the cylinder is an insulating jacket 3 of any suitable insulating material.

The cylinder is provided with a pair of spaced track members 4 which engage the 70 power driven rollers 1. The cylinder rotates on these track rollers during the operation of the device. At each side of the cylinder 2 there is provided a flange 5. Each flange has secured thereto a wall 6 by rivets 70 or otherwise.

The cylinder at each end is provided with removable heads 8 and 9. The removable head 8 is supported upon a circular angle flange 10. It is provided with suitable detachable fasteners 11 which enter slots or the like in the flange 10 by means of which this head can be removed from the cylinder. The cylinder carries a central extension 11' 85 in which a pulverized oil or coal burner 12 is positioned. This burner, of course, is removably positioned in this head and when removed the extension 11' of the head is closed by a suitable door or any other form of closure. The head 9 is similarly secured 90 by means of the flange 13 and carries a coupled extension 14 communicating with a line 15 for carrying from the container products of combustion when the container is being heated and products of distillation 100

when the material therein is undergoing treatment.

The container is preferably rotated by driving the supporting wheels 1, although it 5 may also be rotated by a circular driving gear 15' connected with one of the flanges 5 and meshing with a driven gear at any suitable point.

In operating the apparatus to carry out 10 my process the burner 12 is first inserted in the extension 11', it being understood that both removable heads are tightly connected with the container. If a pulverized coal burner is used and burned only to a state of 15 incomplete combustion the carbonized residue collects within the interior 16 of the container. If oil is used the gaseous products, of course, pass out through the coupling 14 and line 15. The container is heated 20 until the walls thereof approximate a temperature of about 700° C. When this temperature has been reached the burner is withdrawn and coal, oil, or any other material to be treated is introduced through 25 an opening available upon the removal of the head 8 or through an independent opening closed by the door 16' in the removable head 8 of the container. During both the heating operation and the treating operation 30 the container is continuously rotated by the mechanism hereinbefore described. If pulverized coal is introduced to the container the walls 2 thereof must be of such a mass that approximately 5 to 10 pounds of 35 iron is found in the wall of the cylinder for each pound of coal to be charged. With the cylinder wall at approximately 700° C. in temperature, the introduced coal will undergo a thorough carbonization with a drop in 40 the temperature of the walls of the container of about 200° C. During this treatment the volatiles removed are discharged through the coupling 14 and the pipe 15.

If, for any reason, it is desirable to maintain 45 the interior of the container under a superatmospheric pressure the valve 18 in the discharge line 15 is provided to retard the discharge of the produced gases so that a superatmospheric pressure of from 50 pounds upwards is maintained in the container. This is highly desirable when the 50 volatile products are to undergo a cracking treatment, it being understood that a cracking temperature is maintained in the container.

After the material has been carbonized, 55 assuming that coal is to be treated, one or both of the removable heads 8 or 9 are removed by the detachable fasteners 11 and 60 converted residue withdrawn from the container. These removable heads are then again placed in position, a burner inserted and the cylinder tube then heated to a temperature of 700° C. It will be understood 65 that the temperatures employed depend

largely upon the materials being treated and the character of the operation being practiced. With cracking operations relatively higher temperatures will be used, while in the low temperature carbonization of coals and the like lower temperatures will be employed, the temperature used in each operation being well known to the workers skilled in the art. If coal is being carbonized it will be appreciated that it undergoes treatment within fixed limits of temperatures, that is to say, it is introduced to the container when it is heated to its desired maximum temperature and withdrawn from the container when this temperature drops to a predetermined minimum. This results in a production of a carbonized product of a uniform texture. For instance, the product may be uniformly soft for carbonization and likewise the volatile product recovered is of a substantially uniform content. The temperatures employed may, as before stated, be high or low, and, for instance, if secondary distillation products are desired, a high range of temperatures may be used. The process is practiced at all times as a batch process, the container being heated at one time, after which the heating devices are withdrawn and the material to be treated introduced to the container. Plastic masses of coal and oil constitute an ideal mixture to be carbonized in the container, although it is apparent that any type of fuel or in fact other products can be treated. If pulverized coal is being utilized as a fuel that portion of the coal that is reduced to a carbonized residue will collect in the container during the heating operation and thereby augment the supply of coke later produced during a distilling operation.

Having thus described my invention, what I claim is:

1. A carbonizing process which comprises storing a sufficient quantity of heat in a heat absorbing container to carbonize a predetermined quantity of solid material by direct application of heat thereto, discontinuing the application of heat to said container and introducing thereto a charge of solid carbonaceous material having a volatile hydrocarbon content, maintaining carbonizing conditions within said container and thereby carbonizing said material by heat transferred thereto from the container, moving said container while substantially preventing the escape of heat through the walls of said container during the carbonization of the material therein, removing from said container the vapors and gases evolved from the material, and upon completion of the carbonization removing from said container and collecting the carbonized residue.

2. A carbonizing process which comprises storing a sufficient quantity of heat in a heat absorbing container to carbonize a predefer-

5 mined quantity of solid material by the direct application of heat thereto, discontinuing the application of heat to said container and introducing thereinto a charge of solid carbonaceous material having a volatile hydrocarbon content, maintaining carbonizing conditions within said container and thereby carbonizing said material by heat transferred thereto from the container while substantially preventing the escape of heat through 10 the walls of said container, rotating said container during the carbonization of the material therein, removing from said container the vapors and gases evolved from the material, and upon completion of the carbonization 15 removing from said container and collecting the carbonized residue.

3. A carbonizing process which comprises burning fuel within a heat absorbing container until a sufficient quantity of heat has 20 been stored therein to carbonize a predetermined quantity of solid material, then discontinuing the burning and introducing to said container a charge of solid carbonaceous material having a volatile hydrocarbon content, maintaining carbonizing conditions within said container and thereby carbonizing said material by heat transferred thereto from the container while substantially preventing 25 the escape of heat through the walls of said container, moving said container during the carbonization of the material therein, removing from said container the vapors and gases evolved from the material, and 30 upon completion of the carbonization removing from said container and collecting the carbonized residue.

4. A carbonizing process which comprises burning fuel within a heat absorbing container until a sufficient quantity of heat has 40 been stored therein to carbonize a predetermined quantity of solid material, then discontinuing the burning and introducing to said container a charge of solid carbonaceous material having a volatile hydrocarbon content, maintaining carbonizing conditions within said container and thereby carbonizing said material by heat transferred thereto from the container while substantially preventing 45 the escape of heat through the walls of said container, rotating said container during the carbonization of the material therein, removing from said container the vapors and gases evolved from the material, and 50 upon completion of the carbonization removing from said container and collecting the carbonized residue.

5. A carbonizing process as defined in claim 4 further characterized in that said container is rotated during the burning of fuel therein.

6. A carbonizing process which comprises storing a sufficient quantity of heat in a heat absorbing container to carbonize a predetermined quantity of solid material by the

direct application of heat thereto, discontinuing the application of heat to said container and introducing thereinto a charge of solid carbonaceous material having a volatile hydrocarbon content, maintaining carbonizing conditions within said container and thereby carbonizing said material by heat transferred thereto from the container while substantially preventing the escape of heat through the walls of said container, 70 constantly agitating the material within said container during its carbonization, removing and collecting the vapors and gases evolved in said container, and recovering the carbonized residue upon completion of 80 the heat treatment.

7. A process for the destructive distillation of hydrocarbon material having a volatile content which comprises first storing in the walls of a heat absorbing container, by 85 direct application of heat thereto, a sufficient quantity of heat to destructively distill a predetermined quantity of the hydrocarbon material, then discontinuing the application of heat to said container and introducing 90 thereinto the predetermined quantity of the hydrocarbon material, destructively distilling the material in said container by contact with and heat transferred from the walls of the container while substantially 95 preventing the escape of heat from said walls to the exterior of the container, rotating said container during the destructive distillation of the material therein, and removing from said container the vapors and gases 100 evolved from the material.

In testimony whereof I affix my signature.
WALTER EDWIN TRENT.
